UNITED STATES PATENT OFFICE.

ALLAN JOHN DOWNES, OF CROYDON, ENGLAND, ASSIGNOR OF ONE-HALF TO JOHN VENNING, OF LONDON, ENGLAND.

CUT-OUT FOR ELECTRIC INSTRUMENTS, GLOW-LAMPS, AND THE LIKE.

1,217,720.

Specification of Letters Patent. Patented Feb. 27, 1917.

Application filed October 11, 1913. Serial No. 794,720.

To all whom it may concern:

Be it known that I, ALLAN JOHN DOWNES, a subject of the King of England, residing in Croydon, Surrey, England have invented 5 certain new and useful Improvements in Cut-Outs for Electrical Instruments, Glow-Lamps, and the like, of which the following is a specification.

This invention is for improvements in or 10 relating to electrical instruments (which term is used to designate any device actuated by an electric current and provided with leads connected thereto, such devices comprising for example, incandescent electric lamps, electrical measuring instruments 15 and the like), and has for its object to provide a by-pass for electric lamps which are to be burnt in series on the ordinary low pressure supply means, that is to say, at 20 voltages below 250 volts across the parallel mains, and for a series arrangement say of 22 ten-volt lamps, and to provide a safety device for electrical instruments generally in low pressure circuits.

25 The term by-pass in this specification is used to designate means such as hereinafter described whereby two conductors are normally insulated from one another but are automatically brought into electrical connection when they are submitted to a difference of potential considerably higher than the normal.

The by-pass of the present invention relies upon an oxid whose electrical insulating 35 properties are insufficient to resist the higher pressure put upon it as a result of excess voltage in the line or the electric instrument with which it is in parallel becoming inoperative, but which although at such 40 higher pressure it allows current to pass, does not have its insulating properties permanently destroyed by such passage.

The invention will now be described with 45 reference to the accompanying drawings in which—

Figure 1 shows a lamp provided with a by-pass formed by twisting together the leading-in wires, and

Fig. 2 shows a lamp in which the by-pass 50 comprises a ring slipped over the two leading-in wires.

Fig. 3 shows a lamp in which the by-pass comprises a number of metallic rings linked

together to form a chain, the end rings being slipped over the leading-in wires. 55

Figs. 4 and 5 show enlarged views of bypasses comprising several oxid-coated metal rings.

Like reference characters indicate like parts in both the figures. 60

Referring to Fig. 1 the leading-in wires of the lamp, that is, the wires which are connected through the glass bulb A of the lamp to the filament B and to the cap C are usually made in three parts—nickel D D¹ inside the bulb, platinum E E¹ passing through the bulb, and copper or like metal F F¹ between the bulb and the cap. 65

In manufacturing a lamp according to the present invention the wires F F¹ are 70 first heated in air so that an oxid of the metal forming the wires is formed as a coating thereon, and they are then twisted together as shown at G. It is found convenient to give the wires two complete turns. 75 If, as is usual, the wires F F¹ are of copper the thin coating produced by heating the wires appears to be black cupric oxid. The cap is thereafter fitted in the ordinary way.

Fig. 2 shows a modification of the invention in which the wires F F¹ are not heated or twisted together, but are formed in the usual way. A small metallic ring H, say of copper, is heated so as to give it a coating of an oxid of the metal of which it is made, 80 and this ring is slipped over the two wires F F¹ so as to contact with both. Each of the wires F F¹ is thus separated from the ring H by the film of oxid. Otherwise the lamp is made up in the usual way. 85

One convenient method of making oxidized rings is to wind a wire of copper or other metal that is to be used on a thin mandrel, to heat the spiral thus formed and to cut it up into rings. The rings may, however, be oxidized after they are cut up. 95

It has been found that it takes a greater voltage to break down two or more insulated contacts of the kind described than is required to break down one such insulated contact. Thus a single contact may break down on the application of between 30 to 100 volts, while two or more such contacts can sustain a considerably higher voltage. According therefore to the present invention when a lamp or other electrical instru- 100 105

ment is normally operating at a pressure of say 100 volts or upward, two or more insulating contacts as required may be employed. For example two or more oxidized 5 metal rings may be linked together, and the leading-in wires would be arranged to keep the linkage taut.

Fig. 3 shows an electric lamp in which the by-pass is formed of a number of oxid- 10 coated metallic rings H linked together to form a chain, the end rings being slipped over the leading-in wires F F¹. The chain may be kept taut by a plug, such as a cork J, inserted in the lower end of the lamp.

Fig. 4 shows an enlarged view of the leading-in wires of an electric lamp provided with a by-pass formed of a chain of oxid-coated rings H, and in which the leading-in wires F F¹ are twisted to form loops 20 K K¹ through which the end rings of the chain pass.

Fig. 5 shows an enlarged view of the leading-in wires of an electric lamp provided with a by-pass formed of two oxid-coated 25 rings H linked together, one ring being slipped over one leading-in wire, and the other over the second leading-in wire.

It is to be understood that although the ring has been described as oxidized, the 30 leading-in wires may be oxidized.

Taking as an example of the application of the invention a case in which ten 20-volt lamps are burning in series on a 200-volt circuit, the insulation between the two leading-in wires due to the film of oxid is sufficient 35 normally to prevent current flowing between these wires, so that the current passes through the lamps and causes them to glow. Should the filament of a lamp become 40 broken, the passage of current through the lamp is interrupted, and the leading-in wires are immediately subjected to the full pressure of the circuit, that is 200 volts. This abnormally high difference of potential 45 causes current to pass between the leading-in wires across the film of oxid, so that the remaining nine lamps of the circuit continue to burn. It will be appreciated that the inoperative lamp should be replaced as soon 50 as possible as the remaining lamps will be somewhat over-run.

At present telegraph instruments are protected from accidental excess voltage (caused for example by the falling of a power circuit wire on the telegraph wire) by various thermal safety devices, having more or less time lag. When a by-pass according to the present invention is applied to a telegraph or other instrument, the said instrument is 55 provided with two wires connected to its terminals, and the wires themselves are insulated from one another by any one of the forms of by-pass hereinbefore described. For example the two wires might be oxidized 60 and twisted together, or they might be oxi- 65

dized and connected by a metal ring, or an oxidized metal ring could be slipped over unoxidized wires. On the application of excess voltage the instrument is instantaneously short-circuited. When the voltage 70 returns to normal the by-pass can be made effective again by merely tapping it, for the passage of current does not permanently destroy its insulating properties. This is particularly useful in the case of measuring, 75 telegraph or like instruments, since there is no necessity to renew the by-pass after each time it has acted to protect the instrument from excess voltage.

It will be appreciated that the by-pass of 80 the present invention is much less complicated than by-passes in use, and is exceedingly simple to manufacture; moreover it can be manufactured as a separate device as already described in connection with instruments, and may be used many times.

What I claim as my invention and desire to secure by Letters Patent is:—

1. The combination of an electric instrument for use on low pressure circuits, electric leads connected thereto, and a by-pass in parallel therewith, said by-pass being located in an oxidizing atmosphere and comprising a film of oxid connecting the leads but normally insulating one lead from the 95 other.

2. The combination of an electric instrument for use on low pressure circuits, electric leads connected thereto, and a by-pass in parallel therewith, said by-pass being 100 located in an oxidizing atmosphere and comprising an electric conductor connecting the leads, one of the members being oxidized, so that the leads are normally insulated one from another by a film of oxid.

3. The combination of an electric instrument for use on low pressure circuits, electric leads connected thereto, and a by-pass in parallel therewith, said by-pass being located in an oxidizing atmosphere and comprising an oxidized link connecting the two leads to each other, the oxidized film on the link normally insulating one lead from the other.

4. The combination of an incandescent 115 electric lamp for series lighting on low pressure circuits, of a by-pass in parallel therewith, said by-pass being located outside of the exhausted lamp bulb and comprising a film of oxid connecting the two metallic conductors for the lamp but normally insulating one conductor from the other.

5. The combination of an electric instrument for use on low pressure circuits, electric leads connected thereto, and a by-pass 120 in parallel therewith, said by-pass being located in an oxidizing atmosphere and comprising a film of copper oxid connecting two conductors but normally insulating one conductor from the other.

6. The combination of an incandescent electric lamp for series lighting on low pressure circuits, of a by-pass in parallel therewith, said by-pass being located outside the 5 exhausted lamp bulb and comprising a film of copper oxid connecting two conductors but normally insulating one conductor from the other.

In testimony whereof I have signed my name to this specification in the presence of 10 two subscribing witnesses.

ALLAN JOHN DOWNES.
